UNITED STATES PATENT OFFICE.

HIRAM E. PURDY, OF ROCKWELL CITY, IOWA, ASSIGNOR OF THREE-TENTHS TO HIMSELF, THREE-TENTHS TO J. H. BRADT, ONE-TENTH TO T. W. McCRARY, ONE-TENTH TO E. Z. SMITH, ONE-TENTH TO A. F. DEAN, AND ONE-TENTH TO GEO. L. BROWER, ALL OF ROCKWELL CITY, IOWA.

HUSKING-ROLLERS.

937,715.

Specification of Letters Patent.

Patented Oct. 19, 1909.

Application filed May 29, 1908. Serial No. 435,824.

To all whom it may concern:

Be it known that I, HIRAM E. PURDY, a citizen of the United States of America, and resident of Rockwell City, Calhoun county, 5 Iowa, have invented new and useful Husk- 10 ing-Rollers, of which the following is a specification.

A further object of this invention is to provide an improved construction for husk- 15 ing rollers adapted to be employed in removing husks from ears of corn.

My invention consists in the construction, arrangement and combination of elements hereinafter set forth, pointed out in my 20 claims and illustrated in the accompanying drawing, in which—

Figure 1 is a plan of a part of my im- 25 proved husking rollers mounted for rota- 30 tion. Fig. 2 is a cross-section on the indi- 35 cated line 2—2 of Fig. 1. Fig. 3 is a longi- 40 tudinal section on the indicated line 3—3 of Fig. 1.

In the construction of the device as shown 45 the numerals 10, 11 designate husking roll- 50 ers arranged side by side and journaled at 55 their ends in bearings 12, 13. The husking 60 rollers 10, 11 are alike in construction and 65 each of them is formed of a tube and jour- 70 nals in the ends of the tube for rotary 75 mounting in the bearings 12, 13. Intermesh- 80 ing gears 14, 15 are mounted rigidly on the 85 journals in adjacent ends of the tubes, and 90 by means of the gears the tubes are driven in unison. Each tube is formed with a plu- 95 rality of slots 16 spaced throughout its length. Husking pins 17 are provided and 100 are mounted in the tubes and project through the slots 16 thereof. Each husking 105 pin is formed of a single length of wire 110 having a coil 18 intermediate of its ends. 115 One end of the wire is mounted through a 120 block 19 on the interior of a tube and oppo- 125 site a slot 16 and said block is fixed to the 130 tube by screws 20. The end portion of the 135 wire opposite the block 19 is beveled or 140 pointed and projects through a slot 16 of 145 the tube.

Ears of corn to be husked are mounted

on the rollers 10, 11 and said rollers are rotated involutely. During the involute ro- 50 tation of the rollers the pins 17 engage the husks of the ears and pull said husks down- 55 ward through and between contacting per- 60 imeters of the rollers. The pins yield un- 65 der pressure and at times recede within the 70 rollers, because of the coils therein and the 75 inherent resiliency thereof. The pins 17 also may yield longitudinally of the rollers 80 under pressure of ears of corn moving lon- 85 gitudinally, because of the slots 16 in said 90 rollers. Such longitudinal movement of 95 the pins is desirable to prevent damage to the pins by contact with an ear being moved along the rollers by extraneous means.

I claim as my invention—

1. In a corn harvesting machine, a husk- 65 ing roller, comprising a tube formed with 70 apertures, resilient husking pins coiled and 75 fixed at one end within said tube and pro- 80 jecting through said apertures, and means 85 for driving said husking roller.

2. In a corn harvesting machine, a husk- 90 ing roller, comprising a tube formed with 95 apertures, journals in the ends of said tube, 100 resilient pins, each formed of a single length 105 of wire with a coil intermediate of its ends, 110 mounted in said tube and fixed at one end 115 thereto, one end of each pin projecting 120 through an aperture of said tube, and means 125 for driving said roller.

3. In a corn harvesting machine, a husk- 130 ing roller comprising a tube formed with 135 lateral apertures, journals in the ends of said 140 tube, blocks mounted within said tube oppo- 145 site the apertures and resilient pins, each 150 formed of a single length of wire with a coil 155 intermediate of its ends, mounted in said 160 tube and fixed at their inner ends to said 165 blocks, outer ends of the pins projecting 170 through said apertures, and means for driv- 175 ing said roller.

4. In a corn harvesting machine, a pair of 180 husking rollers, comprising tubes mounted 185 for peripheral contact and formed with lat- 190 eral apertures, journals in the ends of said 195 tubes, resilient pins each formed of a single

length of wire with a coil intermediate of its ends and mounted within said tubes, inner ends of the pins fixed to and within the tubes, outer ends of the pins projecting 5 through said apertures and beveled, and means for driving said rollers simultaneously in opposite directions.

Signed by me at Fort Dodge, Iowa, this tenth day of January, 1908.

HIRAM E. PURDY.
